G. A. LE FEVRE,
REINFORCED RAILWAY TIE,
APPLICATION FILED AUG. 17, 1917.

1,295,532.

Patented Feb. 25, 1919.

15 Inventor,
George A. LeFèvre
By his Attorney.

UNITED STATES PATENT OFFICE.

GEORGE A. LE FEVRE, OF NEW YORK, N. Y., ASSIGNOR OF ONE-HALF TO WILLIAM C. HALLECK, OF NEW YORK, N. Y.

REINFORCED RAILWAY-TIE.

1,295,532.

Specification of Letters Patent. Patented Feb. 25, 1919.

Application filed August 17, 1917. Serial No. 186,663.

To all whom it may concern:

Be it known that I, GEORGE A. LE FEVRE, a citizen of the United States, and a resident of the city of New York, county of Queens, and State of New York, having invented a new and useful Improvement in Reinforced Railway-Ties, of which the following is a full, clear, and exact description.

My invention relates to railway ties of reinforced concrete or cement and the object of my invention is to produce a simple, strong and durable tie which can be readily placed, which can be conveniently made at the point where it is used, and which is provided with reinforcement disposed in such a manner as to prevent the tie from crushing beneath the track rails, and also to prevent center bind.

My invention also embodies means for accurately spacing the rails as they are laid on the ties and for preventing the rails spreading by any possibility. My reinforced tie is also preferably made hollow so that it can expand and contract under temperature changes without injury to itself. My tie is preferably made cylindrical to the end that it may be rolled conveniently to the point where it is to be used and may have a slight rocking movement if desired, to compensate for the longitudinal movement of the rails, but certain important features of my invention can be applied to a tie of any shape.

Reference is to be had to the accompanying drawings forming a part of this specification, in which similar reference characters refer to similar parts throughout the several views.

Figure 1 is a cross section through a railway track showing the rails applied to a tie embodying my invention, the tie being shown in side elevation.

Fig. 2 is a view at right angles to that shown in Fig. 1.

Fig. 3 is a detail view showing a form of transverse support or reinforcement in the tie.

Fig. 4 is a broken elevation of the frame-

work comprising the reinforcement of the concrete or cement tie.

Fig. 5 is a cross section on the line 5—5 of Fig. 6 of the complete tie.

Fig. 6 is a broken plan view of the tie.

Fig. 7 is a broken detail section showing especially the means for spacing and bracing the rails.

Fig. 8 is a cross section of a modified shape of the tie; and

Fig. 9 is a broken longitudinal section on the line 9—9— of Fig. 8.

The tie is provided with a reinforcing frame-work consisting of parallel rods 10, which run lengthwise of the tie, and transverse supports engaging the rods, these supports being preferably in the form of a spider shown in Fig. 3, having sockets 11 to 65 engage the rods 10, arms 12 to support the sockets and a hub 13. The socket members 11 are preferably formed with two side pieces 14, which are of malleable metal and may be bent over the rods, as the drawing 70 shows.

It is obvious that the rods 10 can be of any shape and that they need not necessarily be exactly parallel and furthermore that the transverse reinforcement comprising a 75 spider shown in Fig. 3 can be of any form whatever without affecting the invention. This transverse reinforcement can be placed at suitable points in the framework of the tie, but is preferably located below where a 80 track rail comes on the tie so as to make the tie absolutely rigid at this point and prevent the load on the rails from crushing the tie.

The frame-work comprising the rods 10 and the connecting spiders or transverse reinforcement is placed in a mold and embedded in concrete 15, which naturally assumes the shape of the mold and is, as already stated, preferably cylindrical. The 90 tie has preferably a hole 16 extending centrally and longitudinally through it.

To provide for further stiffening the tie and for supporting and spacing the rails, I

preferably embed in the surface of the tie, near the ends, T plates 17, which have anchoring flanges 18 extending into the body of the tie and preferably perforated, as shown at 19 so that the plates can be thoroughly anchored. These flanges 18 should project in between the arms 12 of the spiders or, in any event, they should not come in contact with the longitudinal reinforcements. This is important, because with my construction of tie, the metal fastening and spacing devices at the ends have no metallic connection with each other and so each rail and its connecting parts is insulated from the opposite side so that my construction does not interfere with any ordinary signaling apparatus.

Each T-plate 17 has an upwardly extending flange 20, to which is bolted a brace 21 extending inward and adapted to abut with the flange of the rails 23 (see Fig. 1). For convenience, the brace should be divided with a series of holes 22 so that the fastening bolt can be put through any desired one and through a hole in the flange 20 and thus the braces 21 on the opposite sides of the track can be adjusted so as to hold the rails 23 against any possible spreading, and furthermore, the braces act as gages so that in laying the rails, the latter are simply shoved up until the web of each rail abuts with its corresponding brace and the rails are then accurately spaced.

Obviously, the rails can be fastened to the tie in any convenient way but I have shown the preferred means which is my invention, but which is not here claimed.

As illustrated, each rail sits on a chair or plate 24, having a thickened underside 25 shaped to fit the rail top as shown in Fig. 2. Fastening clips or cleats 26 rest on the chair 24 and on the rail flange and bolts 27 extend downward through the cleats 26, chair 24 and the flanges 28 of the straps 29, which are placed beneath the tie as the drawing shows. The flanges 28 are turned out on the ends of the straps 29 and, in order to provide for a resilient connection, springs 30 can be inserted between the flanges 28 and the nuts of the bolts 27.

To provide for still further resiliency, clamping pieces or cleats 31 can be used as shown on the left hand side in Fig. 2 and these may be secured to the plate or chair 24 by bolts 32 with a spring 33 under the bolt-head, in which case the chairs 24 are bolted directly to the straps 29, as already described.

60 The transverse reinforcement of the tie beneath the load-carrying portions is an important feature of the invention taken in connection with the reinforcing frame-

work and obviously this arrangement can be carried out with ties of any preferred cross-sectional shape. For instance, in Fig. 8 I have shown a rectangular tie having a frame-work like that described and with the spider arranged transversely therein and connected with the longitudinal rods 10, as already described. On the top and bottom of this form of tie, the T-plates 17 are also secured, but the flange 20 is omitted from the bottom as specified, and the tie can connect with its supporting rails, as already stated.

In connection with the transverse reinforcements and the longitudinal rods, a further bracing or trussing effect can be had by securing brace rods 34 to opposite rods 10 and these rods 34 can be arranged to run diagonally and in opposite directions, as shown in Fig. 9. The arrangement of the diagonal braces 34 prevents center binding or the breaking or cracking of the tie near the middle part thereof.

It will be understood that this bracing effect or reinforcing frame described can be applied to ties of any desired cross-sectional shape. It will also be understood that the fastening which I have shown is easy to apply, that the rails can be readily placed and properly spaced and that when placed they can be securely held.

Attention is called to the fact that the plates 17 serve as wear plates and protect the ends of the tie, and also serve as a wearing surface for the rail supports, and as stated, only one of them need be provided with the flange 20.

Attention is also called to the fact that while I have shown a preferred form of tie I claim the right to make the tie in any shape whatever.

I claim:

1. A concrete railway tie having a longitudinally arranged framework entirely embedded therein, said framework consisting of transverse spiders having radial arms with terminal sockets thereon, and longitudinally disposed rods resting in the aforesaid sockets.

2. A concrete railway tie having a longitudinal framework entirely embedded therein, said framework consisting of transverse spiders having arms with sockets thereon, the side members of the sockets being malleable so that they can be bent around the reinforcing rods, and reinforcing rods longitudinally disposed in the tie and resting in the aforesaid sockets.

3. A concrete railway tie having wear plates on the side portions and disposed around the surface thereof, said plates having each a web extending into the tie in which it is anchored, and certain of the

plates having outwardly projecting flanges for the purpose specified.

4. A concrete railway tie having surface wear-plates disposed around the end portions thereof, the wear-plates having inwardly extending webs anchored in the tie and some of the plates having outwardly

extending flanges, and longitudinally adjustable braces on said outwardly extending flanges.

GEORGE A. LE FEVRE.
